(57) **CLAIM**

The ornamental design for a shoe, as shown and described.

DESCRIPTION

FIG. 1 is a side view of a shoe, showing our new design. FIG. 2 is another side view of the shoe of FIG. 1, showing our new design.

FIG. 3 is a front view of the shoe of FIG. 1, showing our new design.

FIG. 4 is a back view of the shoe of FIG. 1, showing our new design.

FIG. 5 is a top view of the shoe of FIG. 1, showing our new design.

FIG. 6 is a bottom view of the shoe of FIG. 1, showing our new design; and,

FIG. 7 is a perspective view of the shoe of FIG. 1, showing our new design.

The broken lines indicate portions of the shoe that form no part of the claimed design.

1 Claim, 7 Drawing Sheets
